CLAIM

The ornamental design for a LED work light as shown and described.

DESCRIPTION

5. LED work light

5.1: Perspective

5.2: Front

5.3: Back

5.4: Left

5.5: Right

5.6: Top

5.7: Bottom

The design is directed to the overall appearance of the LED work light; reproduction 5.1: perspective view; reproduction 5.2: front view; reproduction 5.3: back view; reproduction 5.4: left view; reproduction 5.5: right view; reproduction 5.6: top plan view; reproduction 5.7: bottom view.

Portions of the LED work light are shown in broken lines for illustrative purposes and form no part of the claimed design.

1 Claim, 7 Drawing Sheets
